PHOTOTUBE

Herbert Steyskal, Berlin, Germany, assignor to
General Electric Company, a corporation of
New York

Application July 26, 1938, Serial No. 221,290
In Germany September 27, 1937

8 Claims. (Cl. 250—166)

My invention relates to electron discharge devices and more particularly to phototubes in which secondary emission amplification is produced.

Phototubes are known in which the photoelectric current may be amplified by an additional electrode arranged to release secondary electrons when bombarded by electrons emitted by one of the other electrodes. In these tubes the photocathode and secondary electron emitting cathode or electrode are usually situated opposite each other, while an anode having substantially the shape of a rod is situated midway between the photocathode and the secondary electrode. The photocathode is illuminated either through a window in the secondary electron emitting electrode or where the photocathode is of the transparent type the illumination is transmitted through the photocathode from the rear. This electrode arrangement has the disadvantage that the anode which has the highest positive potential, is situated between the two electron emitting electrodes. In view of the fact that the anode is situated in the path of the electrons moving from the photocathode to the secondary electron emitting electrode, not all of the electrons released at the photocathode can reach the secondary electrode and a certain part of the primary electrons pass directly to the anode without producing an amplification through release of secondary electrons.

In accordance with my invention an electrode is employed in a phototube having a secondary electron emitting electrode which not only produces a shielding effect but also an amplification through a further emission of secondary electrons. This shielding electrode placed in the electron path between the cathode and the secondary electron emitting electrode may form a flat or preferably curved arcuate surface which partially surrounds or encloses the anode.

The principal object of my invention is to provide an improved type of secondary emission amplification phototube in which the primary photoemission is more efficiently utilized in producing an amplified current output.

The novel features which I believe to be characteristic of my invention are set forth with particularly in the appended claims but the invention itself will best be understood by reference to the following description taken in connection with the accompanying drawing in which:

Figure 1 is a perspective view with the envelope partially broken away of a phototube made in accordance with my invention;

Figure 2 is a transverse section taken along the lines 2—2 in Fig. 1; and

Figures 3 and 4 are similar transverse sections of two modifications of phototubes made in accordance with my invention.

One embodiment of a phototube made in accordance with my invention, as shown in Figure 1 comprises an envelope 10 provided with the usual base 11 and stem 12. Supported from the stem 12 is a conventional semi-cylindrical arcuate shaped photocathode 13 which may be coated on its inner or concave surface with any conventional light sensitive coating such as caesium or other alkali metal. Opposite the cathode 13 and preferably concentric therewith, there is provided a secondary electron emitting electrode which, in the modification shown, is in two arcuate shaped segments 14—14a, the inner or concave surface of which is likewise preferably coated with alkali metal for the purpose of increasing its secondary electron emitting properties. Between the photocathode 13 and secondary electron emitting electrode 14—14a and preferably at their common center of curvature is an electron collecting anode 15 which, as shown in the drawing, may be a rod or a conductor extending along the longitudinal axis of the tube.

In accordance with one teaching of my invention, I dispose between the photocathode 13 and the anode 15 a semi-cylindrical or arcuate shaped shield electrode 16, the outer or convex surface of which is similarly coated with a material having high secondary electron emitting properties. The convex surface of the shield electrode 16, however, may be smooth or shiny, such a surface also providing a good secondary emitting surface. As shown in the drawing, the shield electrode 16 is imperforate to prevent electrons from the cathode 13 flowing directly to the anode 15. Positive potentials are applied to the electrode 14—14a, the shield 16 and the anode 15 such as by the batteries 17, 18 and 19 so that these electrodes are progressively more positive with respect to the photocathode in the order named.

As a result of the shape of, and the field distribution between the electrodes, the photoelectrons liberated from the photocathode 13 under the influence of light projected thereon through the envelope and between the secondary emitting electrode 14—14a, are focused and directed upon the convex surface of the shield electrode 16 whereupon secondary electrons are liberated from the convex surface and directed upon the secondary cathode 14—14a by reason of the dif-

ference in potential existing between these electrodes. The entire quantity of electrons are directed to the anode 15 where they are collected, and led to the output circuit where they may be 5 utilized in the impedance 20.

By the use of my new and novel shield cathode, I obtain additional secondary electron emission and prevent the passage of electrons from the cathode 13 directly to the anode 15 where 10 they would be collected without producing any secondary electron emission from the concave surface of the secondary cathode 14-14a.

While I have shown in connection with the above illustrative example one modification of a 15 phototube incorporating my invention, it may be desirable for certain applications to provide the photocathode 13 and secondary electrode 14 directly on the wall of the envelope 10, such as shown in Figure 3. In this modification, I prefer 20 to make the photocathode 13 of the semi-transparent type so that light may be directed upon the photocathode from its convex side. In this modification of my invention, it is unnecessary to form the secondary electron emitting electrode 14 25 in segmented sections so that it likewise may be deposited directly, preferably as a metallic film, on the inner wall of the envelope 10 opposite the photocathode 13, the anode 15 and shield cathode 16 occupying corresponding positions as 30 shown in Figure 1.

A further modification of my invention is shown in Figure 4 in which the photocathode 13 lies in a single plane, the secondary electron emitting electrode 14-14a being segmented and 35 oppositely disposed therefrom. Intermediate the photocathode 13 and the section 14 of the secondary cathode, I provide an anode 15 and shield cathode 16 similar to the form shown in Figure 1 and likewise between the section 14a and the 40 cathode 13 another anode 15a and associated shield cathode 16a. In this modification the two sections 14-14a of the secondary cathode are connected together as are the anodes 15-15a and shield cathodes 16-16a, these electrodes 45 being similarly connected to sources of potential as shown in Figure 1.

While I have indicated the preferred embodiments of my invention of which I am now aware and have also indicated only one specific application 50 for which my invention may be employed, it will be apparent that my invention is by no means limited to the exact forms illustrated or to the use indicated but that many variations may be made in the particular structure used and 55 the purpose for which it is employed without departing from the scope of my invention as set forth in the appended claims.

I claim:

1. A phototube including an envelope enclosing an arcuate shaped photocathode, a secondary electron emitting electrode having arcuate shaped segments oppositely disposed from said photocathode, an electron collecting anode symmetrically positioned with respect to said photocathode and said secondary emitting electrode and a secondary electron emitting shield between said anode and said photocathode partially enclosing said anode.
2. A phototube enclosing within an envelope a photocathode, an oppositely disposed multiply segmented secondary electron emitting electrode, an anode between each of the segments of said electrode and said photocathode and a secondary

electron emitting shield between each anode and said photocathode

3. A phototube including an envelope containing a photocathode in the form of a plate of extended area, an output anode, an imperforate 5 secondary electron emitting electrode having an extended area less than that of said photocathode positioned between said anode and said photocathode to prevent photoelectrons moving directly from said photocathode to said anode, and another secondary electron emitting electrode 10 facing said photocathode and wholly exposed to the side of said anode opposite said photocathode.

4. A phototube including an envelope containing a photocathode, an output anode, an arcuate 15 secondary electron emitting shield electrode partially surrounding said output anode and having its convex surface facing said photocathode and having an opening on the side thereof away from said photocathode, said arcuate shield electrode 20 being between said photocathode and said anode, and another secondary electron emitting electrode exposed to said anode through the opening in said arcuate secondary emitting shield electrode, oppositely disposed from said photocathode 25 and lying wholly beyond said arcuate secondary emitting electrode with respect to said photocathode.

5. A phototube including an envelope enclosing 30 a photocathode, a secondary electron emitting electrode having an arcuate segment with its concave surface facing, and oppositely disposed from, said photocathode, an electron collecting anode symmetrically positioned with respect to said photocathode and said secondary emitting 35 electrode, and a secondary electron emitting shield electrode between said anode and said photocathode partially enclosing said anode.

6. A phototube including an envelope containing 40 an arcuate photocathode, an output anode substantially at the center of curvature of said arcuate photocathode, an arcuate secondary electron emitting electrode partially surrounding said anode having its convex surface facing the concave surface of said photocathode and another secondary emitting electrode oppositely disposed from said photocathode and said arcuate secondary emitting electrode with respect to 45 said anode and exposed to said anode.

7. A phototube enclosing within an evacuated 50 envelope an arcuate photocathode, an arcuate secondary electron emitting shield electrode having the same center of curvature as and a smaller radius of curvature than that of said photocathode positioned with its convex surface facing the 55 concave surface of said photocathode, an output anode at the center of curvature of said shield electrode and a secondary emitting electrode oppositely disposed from said photocathode and said anode and lying wholly beyond the region 60 between said photocathode and said arcuate shield electrode.

8. A phototube including within an evacuated envelope a semitransparent photocathode, an output anode, an imperforate arcuate secondary 65 electron emitting electrode positioned between said anode and said photocathode with its concave surface facing said anode and intercepting all direct paths between the surface of said photocathode and said anode, and a secondary electron emitting electrode facing said photocathode and wholly exposed to said anode.

HERBERT STEYSKAL.
